10 Claims. (Cl. 62—118)

- My invention relates to a device for cooling a heat generator by means of a circulating auxiliary liquid, and more particularly to a device for periodic absorption refrigerating apparatus.
- 5 5 Devices for the transfer of heat which operate with an auxiliary liquid circulating between a heat generator and the heat consumer are known to those skilled in the art. Thus, for instance, it is common practice both for heating and cooling purposes to transfer the heat by means of a circulating auxiliary medium which remains liquid during the entire process. Analogously, an auxiliary liquid may also be employed for the above purpose, the circulation of which is effected by the alternate evaporation and condensation of the liquid.
- 10 10 My invention contemplates a device for the transfer of heat with an auxiliary liquid circulating between the heat generator and the heat consumer, and its object is to provide two circulating paths for the auxiliary liquid which are so arranged in relation to each other that the auxiliary liquid can only circulate in the one circulating path at temperatures which lie below 15 its boiling point, whereas at temperatures above the boiling point a circulation may also take place in the other circulating path by the alternate evaporation and condensation of the liquid. In effecting such a transfer of heat, the heat consumer designed as a cooler for the auxiliary liquid may be carried out so as not to be completely filled with the auxiliary liquid. In this case a conduit leads from the heat generator to the cooler below the surface of the liquid contained therein and another conduit above the same, whereas a common conduit returns to the heat generator.

The device according to the invention may be used for various practical purposes. It is particularly suitable as safety device against undue rises in temperature in the generator. In case the circulation of liquid should be interrupted in the conduit entering at a point below the level of the liquid; for instance, by closing a cock or valve, the temperature in the generator may rise within unreasonable limits. In this case the conduit entering the cooler above the surface of the liquid and by-passing the valve prevents the temperature in the generator from obtaining too high a value, since in this case the circulation of the liquid is introduced by the alternate evaporation and condensation of the liquid.

The accompanying drawing represents an embodiment in a diagrammatic form of a device for carrying off the heat of absorption of a

periodic absorption refrigerating apparatus which operates with solid absorption media.

Referring to the drawing, the reference character 1 denotes the generator-absorber containing a solid absorbent consisting, for instance, of calcium chloride saturated with ammonia. From the generator-absorber 1 the refrigerating medium passes during the generating period through a conduit 2 into an air-cooled condenser 3 and thence into a container 4 communicating with an evaporation coil 5 projecting into the cooling chamber 6, the coil 5 being placed in a receptacle 7 containing a salt solution. The generator-absorber is surrounded by a cooling jacket 7 from the upper part of which a conduit 8 extends to an air-cooled return cooler 9, whereas a conduit 10 connects the return cooler to the lower end of the cooling jacket 7. A valve 11 serves to interrupt the circulation of the auxiliary liquid during the generating period, the valve being controlled in such a manner as to be open during the absorption period and closed during the generating period. The control is effected by means of an electromagnet 20 which, when energized, closes the valve 11. 18 designates the electrical heating element for the generator-absorber 1. During the generating period the heating element is switched in at the same time with the electromagnet 20 by a contact making clock 19. During the absorption period the contact making clock breaks in a well-known manner the circuit for the heating element 18 and the electromagnet 20. 12 is a cooler which acts at the same time as an expansion vessel for the auxiliary liquid and is provided at the top with an inlet connection 13 which, if desired, may be designed as a safety valve. The expansion vessel 12 takes up the increased volume of the cooling liquid during the heating so as to prevent an undue increase in pressure in the system. A conduit 16 connects the expansion vessel 12 with the return cooler 9. A conduit 14 extending from the upper part of the cooling jacket 7 enters the expansion vessel 12 at a point above the highest possible level of the liquid.

As heat carrier an auxiliary liquid is employed in this apparatus, the boiling point of which is so high that normally no evaporation of the cooling medium may take place. Turpentine oil and transformer oil are, for instance, suitable for this purpose. Liquid mixtures or solutions may also be employed. The space in the expansion vessel 12 above the surface of the liquid is preferably filled with an inert gas, for instance nitrogen, in order to avoid a decomposition of the liquid.

Under normal working conditions the auxiliary liquid contained in the generator cooling jacket 7 is heated during the absorption period by the heat of absorption so that the liquid rises through 5 the conduit 8 into the return cooler 9, and there the liquid gives off the heat to the atmosphere with the aid of radiating ribs. The cooled-off liquid returns then from the return cooler 9 through the conduit 10 to the lower part of the 10 cooling jacket 7. During the generating period the automatic circulation must be interrupted in order not to carry off unnecessarily the heat to the atmosphere. To this end, the valve 11 is closed in the above described manner. Since the 15 generator 12 is electrically heated and the valve 11 is electromagnetically controlled in accordance with the contact making clock 19, it may happen that owing to a failure of the contact making clock, the generator-absorber 1 continues being 20 heated and that the valve 11 remains closed. In this manner such high temperatures may prevail in the generator as to give rise to a breakdown of the apparatus. In the apparatus according to the invention this drawback is avoided, 25 for as a result of the higher temperature prevailing in the generator the normally liquid cooling agents of the circulating system begins now to evaporate in the generator cooling jacket 7. The cooling medium rises in the conduit 14 by means 30 of vapor bubbles and passes along with the latter into the expansion vessel 12 where the vapor is condensed. To accelerate the condensation it is preferable to provide the expansion vessel with radiating fins 15. Owing to the thermo-siphon 35 action of the vapor bubbles in the conduit 14 a circulation of the cooling medium is effected from the cooling jacket 7 through the conduit 14, the expansion vessel 12, the connecting conduit 16, the return cooler 9 and through the conduit 10 40 back to the cooling jacket 7 so that the excess heat from the expansion vessel 12 and the return cooler 9 is given off to the atmosphere.

I claim as my invention:

1. In a device for cooling a heat generator, a 45 circulating system comprising a part in heat exchange relation with the heat generator, a heat consuming device and conduits therefor, a liquid in said circulating system having a boiling point higher than the maximum temperature prevailing under normal operating conditions, and a safety device connected with said circulating system operable as a result of the boiling of the liquid upon undue rises in temperature of the heat generator.
2. In a device for cooling a heat generator, a 55 circulating system comprising a part in heat exchange relation with the heat generator, a cooling medium in said circulating system having a boiling point higher than the maximum temperature prevailing under normal operating conditions, means for interrupting the circulation in said system, and means for insuring a sufficient amount of circulation of the cooling medium during said interruption to maintain the temperature at a 60 safety point and prevent undue rises of said temperature.
3. In a device for cooling a heat generator, a 70 circulating system comprising a part in heat exchange relation with the heat generator, a branch circuit communicating with said system, and a cooling medium having a boiling point such that said medium circulates as a liquid in said system under normal operating conditions and vaporizes into the branch circuit under abnormal operating 75

conditions whereby to prevent undue rises in temperature of the heat generator.

4. In a device for cooling a heat generator, a 5 circulating system comprising a part in heat exchange relation with the heat generator, a cooling medium for circulating in said system, means in said circulating system for interrupting the flow of the cooling medium during heating operation of the generator and normal temperature operations thereof, and means for by-passing said medium about said interrupting means when undue rises in temperature of the heat generator occur.

5. A device for cooling a heat generator, comprising a circulating system having a part in heat 15 exchange relation with the heat generator and a by-pass conduit communicating therewith to form two circulating paths, and an auxiliary liquid adapted to circulate in one of said paths at temperatures in the heat generator below the boiling 20 point of said liquid and to circulate in the other path incident to vaporization of said fluid at temperatures prevailing in the heat generator above the boiling point of said liquid.

6. A device for cooling a heat generator, comprising a circulating system having a part in heat exchange relation with the heat generator and a by-pass conduit communicating therewith to form two circulating paths, an auxiliary liquid adapted to circulate in one of said paths at temperatures 30 in the heat generator below the boiling point of said liquid and to circulate in the other path incident to vaporization of said liquid at temperatures prevailing in the heat generator above the boiling point of said liquid, and a cooling means 35 in said by-pass conduit for cooling the liquid under the last mentioned conditions.

7. In a device of the class described the combination of a heat generator, a liquid container surrounding the generator, a cooling liquid in said 40 container, a liquid cooler, conduits connecting the cooler with the container to form a liquid circulating system, a valve in said system for interrupting the circulation, and a safety means for receiving a part of the cooling medium comprising 45 an expansion chamber connected to said system and adapted to relieve the system of excess pressure when undue temperature occurs in the generator during the interruption of the circulation.

8. A device as claimed in claim 7 wherein the expansion chamber comprises a condenser and said condenser is connected to the circulating system by a rising pipe in which the vapors from the liquid raise said liquid to the condenser for condensation and return to the said system.

9. In a device for cooling a heat-generator, a circulation system comprising a part in heat exchange relation with the generator, a circulating medium in said system partly filling the same, 60 cooling means for cooling the circulating medium, two conduits between said cooling means and the part in heat exchange relation with the generator arranged to convey the circulating medium from the part in heat exchange with the generator to the cooler, one of the said conduits being connected with the cooling means at a point above the surface of the circulating medium and the other connected at a point below the level of the medium, and a conduit arranged to convey the 65 circulating medium from the cooler back to the part in heat exchange with the generator.

10. In a device for cooling a heat generator, a circulating system comprising a part in heat exchange relation with the generator, a circulating 70

5 medium in said system, comprising a liquid partly filling the same, cooling means for cooling the circulating medium comprising two parts arranged one above the other, one of said parts serving as a condenser for the circulating medium and the other acting as a liquid cooler, two conduits between said cooling means and the part in heat exchange relation with the generator arranged to convey the circulating medium from

the part in heat exchange with the generator to the cooler, one of said conduits being connected with the cooling means at a point above the surface of the circulating medium and the other connected at a point below the level of the medium, and a conduit arranged to convey the circulating medium from the cooler back to the part in heat exchange with the generator.
